CLAIM

The ornamental design for a smart ring, as shown and described.

DESCRIPTION

FIG. 1 is a front, bottom perspective view of a first embodiment of a smart ring, showing our new design;

FIG. 2 is a front, bottom, right perspective view thereof;

FIG. 3 is a rear, top, right perspective view thereof;

FIG. 4 is a top view thereof;

FIG. 5 is a bottom view thereof;

FIG. 6 is a left view thereof;

FIG. 7 is a right view thereof;

FIG. 8 is a front view thereof; and

FIG. 9 is a rear view thereof.

FIG. 10 is a front, bottom perspective view of a second embodiment of the smart ring, showing our new design;

FIG. 11 is a front, bottom, right perspective view thereof;

FIG. 12 is a rear, top, left perspective view thereof;

FIG. 13 is a top view thereof;

FIG. 14 is a bottom view thereof;

FIG. 15 is a left view thereof;

FIG. 16 is a right view thereof;

FIG. 17 is a front view thereof; and,

FIG. 18 is a rear view thereof.

The broken lines in the figures illustrate portions of the smart ring that form no part of the claimed design. The oblique shade lines in the figures show transparency or translucency.
